Chicago, Ill., assignors to Continental Scale Corpora-
tion, Chicago, Ill., a corporation of Delaware

Filed Apr. 28, 1965, Ser. No. 85,001

Term of patent 14 years

(Cl. D52—10)

The figure is a front perspective view of a weighing scale embodying our new design, the undisclosed end of the weight beam being essentially the same as the end shown and the rear of the weight beam being plain and unornamented.

We claim:

The ornamental design for a weighing scale, as shown and described.
